Jacob Gang, Fayette Co Pennsylvania

Letters Patent

The Schedule referred to in these Letters Patent and making part of the same containing a description in the words of the said Jacob Gang himself, of his improvement in the machine for hulling clover seed.

Be it known that Jacob Gang of Fayette County and State of Pennsylvania have made an improvement in the machine for hulling clover seed, which is described as follows. The frame or box is made of any convenient size adapted for the machine. It is enclosed at the sides and ends like a box and covered at the top with a lid.

The hulling Cylinder 13, made of wood and covered with sheet iron or any suitable material and is of any convenient length and diameter. It turns on guides and bears on the frame. The sheet iron covering is furnished all round so as to make projections at about $\frac{1}{8}$ to $\frac{1}{3}$ of an inch apart.

The Pivoted or bed is made of a diameter a little greater than the cylinder it extends about three fourths around the cylinder and rests in a groove placed underneath. There may be other spiral or any other springs. It is to be loosely furnished by the cylinder but the projections are inserted. It is placed at such a distance from the cylinder that it will turn freely but not the seed. The spur is attached or attached to the side of the cylinder and may be either a pulley with a strap or belt, passing round a drum, or it may be a small cog wheel worked into a large one.

The machine may be turned by hand or horse power.

Operation. The clover seed after having been threshed from the straw is put into a hopper placed over the cylinder & bed. The machine being put in motion causes the seed between the cylinder and a move bed and there it is rubbed out. The seed and chaff then pass thro the holes in the board and bed properly separated and it is saved in the usual way.

For a further illustration of my invention, I refer to the model and drawing of the same deposited in the Patent Office — W. H. G.

claim as my invention of which I wish to name by Letter Patent in the
before described machine for hauling down and in the general arrangement
and combination for the purpose aforesaid forth.

In testimony whereof I have hereunto subscribed my name this 10th
day of March 1833.
